UNITED STATES PATENT OFFICE

JOHN WARREN VEDDER, OF WORCESTER, MASSACHUSETTS, ASSIGNOR TO RICE, BARTON & FALES, INCORPORATED, OF WORCESTER, MASSACHUSETTS, A CORPORATION OF MASSACHUSETTS

LAMINATED DOCTOR

Application filed April 2, 1928. Serial No. 266,613.

This invention relates to doctors for calenders, dryers or other rolls. Its object is to provide a doctor of a flexible nature with means whereby the edge of the doctor blade in contact with the roll will be sufficiently flexible longitudinally but not materially so transversely.

Reference is to be had to the accompanying drawing which is a transverse sectional 10 perspective view of a doctor showing a preferred form of this invention.

It is desirable to so construct the doctor blade in contact with the roll, that it will have sufficient longitudinal flexibility to so 15 conform its edge as to accommodate itself to any unevenness in the surface of the roll. However, flexibility in the transverse direction is undesirable. In a doctor which is flexible both longitudinally and transversely, 20 pressure on the doctor causes the blade to turn up on an axis parallel with the roll, and provides a wedge shaped recess at the end of the blade wherein paper, grit, etc. tends to force itself and cause the doctor to be ineffective. The grit will get into this wedge- 25 shaped recess and score the roll, causing considerable damage.

My invention comprises a flexible blade formed in laminated sections so that its 30 edge will be longitudinally flexible but will be prevented from bending transversely to such a degree as to permit said recess to be formed.

In the drawing I have shown the invention 35 as applied to a rigid doctor back 10 which is employed in connection with the usual roll 11. This doctor back has a portion projecting toward the roll, preferably above the center thereof. On this back is mounted, by screws 40 or the like 12, the doctor blade. This is made up of a series of flexible leaves 13 and 14, each of which is adapted to engage the surface of the one below it along a line at a short distance from its edge. Thus the blade 45 is backed up to prevent its operative edge bending upwardly far enough to provide a wedge shaped recess at its end where it touches the roll 11.

Although it will be seen that this blade is 50 flexible, its flexibility operates only in the

comparatively narrow space between the edge of the leaves 13 and the roll. It is free to yield beyond that edge but is held down at a plurality of points at a distance from the doctor back and along lines parallel with 55 the roll and progressively farther away from it.

In this way it will be seen that while the flexibility of the blade is taken advantage of to hold the blade against the roll and allow the blade to bend slightly all along its edge to accommodate any irregularities in the surface of the roll, it is held from any material transverse bending by its successive leaves. 60

This provides for the flexibility of the blade in a lengthwise direction and allows for the blade to accommodate itself perfectly to any unevenness of the roll. At the same time it avoids material flexibility in a transverse direction. The backing up of the blade by the upper leaves causes it to act practically as a rigid blade as far as transverse bending is concerned, although made of flexible material. 65

It will be noted that the blade 14, in the embodiment shown is unsupported from below except by the rigid member 10, the leaves 13 all operating on the upper side of the blade 14. It is to be understood that the 70 terms "upper" and "below" are but relative and that if the roll 11 is reversed and the doctor accordingly turned about that such arrangement is contemplated by the present invention. 75

Although I have illustrated and described only one form of the invention I am aware of the fact that modifications can be made therein without departing from the scope of the invention as expressed in the claims. 80

Therefore I do not wish to be limited in this respect but what I do claim is:—

1. A doctor for the purposes described comprising a flexible blade mounted at a distance from its point of contact with the surface which it engages and made up of a series of flexible leaves, each bearing on the one below along a line at a short distance from the edge thereof and parallel therewith to prevent the blade from bending or getting out 95 100

of position along that line and also prevent enough transverse flexibility to cause the upper edge of the doctor to become spaced from the roll at any point.

5 2. A doctor for the purposes described, comprising two separate flexible leaves, a rigid support by which said leaves are carried, the lower leaf projecting beyond the edge of the support and unsupported from 10 below beyond said edge, the upper leaf projecting beyond said edge and its edge engaging the lower leaf along a line parallel to the operative edge of the lower leaf and said edge of the support and at a material 15 distance from both.

3. A doctor for the purposes described, comprising a flexible blade, a rigid support having a front edge parallel with the operative edge of the blade, said blade being secured to said support, projecting beyond the edge thereof, and unsupported from below beyond the edge of the support, and a series of entirely separate flexible leaves, all secured to the support at their rear edges and 25 each projecting over the one next below to a line part way between the line along which it is secured to the support and the outer edge of the blade or leaf next below.

4. A doctor for the purposes described, 30 comprising a flexible blade, a rigid support therefor beyond the edge of which the blade projects, and a spring leaf secured along one edge to said support and projecting over and engaging said blade along an area which 35 is unsupported directly by said support, said leaf being free from the blade.

In testimony whereof I have hereunto affixed my signature.

JOHN WARREN VEDDER.
